(57) CLAIM

We claim the ornamental design for a washing machine with full-touch LCD having graphical user interface, as shown and described.

DESCRIPTION

FIG. 1 is a front view of a washing machine with full-touch LCD having graphical user interface showing our new design; and,

FIG. 2 is an enlarged view thereof, but shown without broken lines for ease of illustration.

The broken lines shown in the drawings represent the washing machine with full-touch LCD and form no part of the claimed design.
